FOLDING SHAVING BRUSH

William B. Grogan, Long Beach, Calif.

Application December 18, 1945, Serial No. 635,669

1 Claim. (Cl. 15—185)

1

This invention relates to shaving brushes, and more particularly to a folding shaving brush wherein the bristle portion can be enclosed in the handle portion when the brush is not in use.

A main object of the invention is to provide a novel and improved folding shaving brush structure which is very simple and inexpensive to manufacture and which is adapted to be folded to form a very compact article when not in use, said brush being easily unfolded when it is desired to employ it in shaving.

A further object of the invention is to provide an improved shaving brush of the folding type wherein the bristles are maintained in sanitary condition when not in use and wherein the brush is adapted to form an article of minimum volume when in its folded condition.

Further objects and advantages of the invention will appear from the following description and claim, and from the accompanying drawings, wherein:

Figure 1 is a side elevational view partly in cross-section of a shaving brush constructed according to this invention, said brush being shown in folded position.

Figure 2 is an end elevational view of the folded brush of Figure 1.

Figure 3 is a longitudinal cross-sectional view taken on line 3—3 of Figure 2.

Figure 4 is a transverse cross-sectional view taken on line 4—4 of Figure 3.

Figure 5 is a longitudinal cross-sectional view of the brush of Figure 1 shown in unfolded position.

Figure 6 is a transverse cross-sectional view taken on line 6—6 of Figure 5.

Figure 7 is a detail transverse cross-sectional view of the brush of Figure 1 showing the parts thereof in partly unfolded position.

Referring to the drawings, 11 designates the housing of the brush, said housing being generally rectangular in plan and in cross-section, and comprising a cup-shaped base portion 12 having longitudinally hinged thereto at 18 a cup-shaped cover portion 13, the hinge being located in the median horizontal plane of housing 11 at a longitudinal side wall thereof whereby base portion 12 and cover portion 13 are substantially of the same size and shape.

A brush 14 conforming generally to the shape of the inside of housing 11 is hinged at 15 to the upper edge of the forward end wall 16 of base portion 12, said brush 15 being adapted to be swung through an angle of 180° from its folded position, shown in Figures 1, 3 and 4 to its unfolded posi-

2

tion, shown in Figure 5 in which the base portion of brush 14 is in abutment with the forward end wall 16 and is adapted to be rigidly locked in unfolded position by abutment with the forward end wall 17 of cover portion 13 when said cover portion is in its closed position with respect to base portion 12. A leaf spring 19 carried by base portion 12 cooperates with a detent lug 20 formed inside cover portion 13 to releasably retain the cover portion in closed position, said leaf spring having a manual release lug 21 which projects through an opening in side wall of base portion 12 for disengaging spring 19 from detent lug 20 when it is desired to unfold cover portion 13.

Hinged to the upper longitudinal edge of base portion 12 opposite main hinge 18 at 23 is an angular guard member 22 adapted to overlie the bristle portion of brush 14 when the brush is in folded position within base portion 12. Guard member 22 is adapted to snugly urge the bristles into compressed position inside the housing to facilitate the closing of cover portion 13 when the brush is being folded up. When the brush is to be unfolded, guard member 22 is rotated 90° to the position shown in Figure 7 and cover member 13 is rotated 90° in the opposite direction, as shown in Figure 7, whereby clearance is provided for rotating brush 14 from its folded to its unfolded position. In folding the brush to its inoperative position the reverse procedure is followed.

A plurality of ventilation openings 24 are provided in base portion 12 and in cover portion 13 adjacent the bristles to permit air to be circulated past brush 14 when said brush is in folded position in housing 11.

While a specific embodiment of a folding shaving brush has been disclosed in the foregoing description it will be understood that various modifications within the spirit of the invention may occur to those skilled in the art. Therefore it is intended that no limitations be placed on the invention other than as defined by the scope of the appended claim.

What is claimed is:

A folding shaving brush comprising a housing having rectangular walls, said housing including a pair of cup-shaped segments hinged together at a first longitudinal edge of one of the segments, 50 a brush member hinged to the upper edge of a forward end wall of one of the segments for rotation through an angle of substantially 180° from a folded position within the housing to an unfolded position outside the housing, said brush member being provided with a base portion and

being adapted to be locked in unfolded position by abutment of said base portion with the forward end walls of the cup-shaped segments, and a guard member L-shaped in transverse section hinged at one edge thereof to the longitudinal edge of said one segment opposite said first longitudinal edge, said guard member being adapted to overlie the brush member when it is in its folded position.
